UNITED STATES PATENT OFFICE.

WILLIAM W. DEAN, OF ELYRIA, OHIO, ASSIGNOR TO THE DEAN ELECTRIC COMPANY,
OF ELYRIA, OHIO, A CORPORATION OF OHIO.

DYNAMO-ELECTRIC MACHINE.

1,026,737.

Specification of Letters Patent.

Patented May 21, 1912.

Application filed January 28, 1910. Serial No. 540,591.

To all whom it may concern:

Be it known that I, WILLIAM W. DEAN, a citizen of the United States, residing at Elyria, in the county of Lorain and State 5 of Ohio, have invented certain new and useful Improvements in Dynamo-Electric Machines; and I do hereby declare the following to be a full, clear, and exact description of the invention, such as will enable others 10 skilled in the art to which it appertains to make and use the same.

My invention relates to generators for electric currents, and more particularly for such as are designed for the purpose of producing a spark to explode the charge of an 15 internal combustion engine. I have endeavored to produce such a machine which is especially adapted for use on automobiles, motor boats, flying machines and other 20 vehicles. With this object in view I have provided a simple compact machine which requires little space to accommodate it and which is inaccessible to dirt, water and other objects which would cause deterioration of 25 the machine. It is also so built that it can be firmly secured to any part and is not subject to being injured or shifted upon its supports by such blows as these machines are, in the course of their use, liable to receive. 30 In this particular use, the spark producing devices should be so adjustable as to change the time of sparking in order that the relation between the time of sparking 35 and the position of the piston in the engine may be adjusted. This is due to the fact that there is a slight interval of time between the spark and the explosion of the charge during which the charge is being ignited. There is one point in the revolution 40 of the piston at which it is most desirable that the explosion should take place. This point I will call the critical point. The sparking should take place when the piston is in such a position that the interval 45 of time existing between the sparking and the explosion is sufficient to permit the piston to move from that position to the said critical position. It will be readily seen that the piston will require different distances at different speeds of the engine, and that if the spark were exploded during a 50 slow movement of the piston at a point of time for which it had been set for a faster speed, the explosion would take place before the piston had reached the critical

point. To remedy this, the time at which the spark takes place should be adjusted relatively to the position of the piston in the cylinder. Thus, when the piston is moving slower causing the spark to occur later, 60 I may allow just the proper time for the piston to reach the critical point before the explosion. To accomplish this I make my field magnets adjustable with respect to the other parts of the mechanism. Since the 65 maximum spark takes place at the time the coil leaves the edge of the pole piece, and since the engine and the generator are in synchronism, by changing the pole I may change the time of sparking. In my ma- 70 chine I have endeavored to realize all these objects and to produce a device which may be manufactured by standard machinery with as few operations as possible and the members easily assembled. The parts of 75 my machine may also be manufactured from regular stock, such as is in the market, or can be produced without the construction of expensive machinery.

It must be readily seen that a machine 80 which cannot be manufactured, is useless, and that the production of a machine which is what is known in shop parlance as a good manufacturing proposition, is more useful than one whose construction demands the 85 production of new and expensive machinery, expert labor, and special designing. This is particularly true in view of modern labor conditions. The structure of my machine is such that I have been able to adopt stand- 90 ard manufacturing methods to produce the parts thereof. I show the exterior casing as a tube, though I may, of course, use any other shaped stock adapted for the purpose. The field magnets consist of straight steel 95 bars which I may roll or press into a shape to conform to the interior periphery of the casing. Those shown consist of straight bars whose cross section would be the arc of a circle. These magnets are fastened to 100 the casing on the interior thereof. In the form shown in the drawing I have illustrated a pair of magnets, one shorter in length than the other, fastened together and a pole piece which fills up the space be- 105 tween the two ends of the magnets and extends part way over the exterior surface of the smaller magnet. The casing is closed at each end. The whole casing is journaled upon standards so that it may be rotated 110

about its principal axis. I show two armatures rigidly fastened together mounted within the casing and adapted to be rotated to cut the flux from the field, each 5 armature being mounted adjacent to a pole of the magnets. Of course I may use only one armature and connect the opposite magnets together at the other end.

Another object which I have in view in 10 thus constructing my machine, is to produce a device whose parts will be rigidly fastened together and will not be liable to shift during the use of the machine. By 15 making the parts from standard stock or from stock which is formed for the purposes of this device by simple operations, I am enabled to construct parts which do not vary in shape from other parts of like kind. Thus, in manufacturing these 20 machines, I can depend upon the relation between the parts being about the same in each construction. Owing to these two things I am enabled to reduce the air gap in the magnetic circuit and to rotate the armature 25 at a higher rate of speed.

These and other objects of my invention I realize in the particular form which I have shown.

The invention itself will be best understood by reference to the following description when taken in connection with the accompanying illustration, showing one specific embodiment thereof, while its scope will be more particularly pointed out in the 35 appended claims.

Figure 1 is a vertical cross section taken through the line I—I of Fig. 2. Fig. 2 is a cross section taken through the line II—II of Fig. 1. Fig. 3 is a section taken through 40 the line III—III of Fig. 1. Fig. 4 is a diagram of a part of the circuit arrangements together with the rotating cam on the end of the armature shaft.

Referring to the drawings, I show standards 45 1 and 1' which at the bottom spread out into feet 2. These feet extend the length of the machine as shown in Fig. 1. The machine is fastened to a base by fastening devices which connect the feet thereto. At 50 the upper end of the standards I show bearings 3 for the machine proper.

4 is a hollow casing shown in this form as a cylinder. I may cut this from any standard tubing. The ends of the casing are 55 closed by the members 5 and 6 which effectively seal up the parts of the machine. The parts 5 and 6 extend at the center forming the hollow trunnions 7 and 8. These trunnions are journaled in the bearings 3 so that the whole casing may be rocked 60 therein.

At 9 I show a device by which the casing may be rotated. I do not contemplate a 65 complete rotation of this casing, but arrange to move it through an angle sufficient for the

purposes of my invention. The field magnets consist of permanent steel bars 10, 11, 12 and 13. These bars are straight along their longitudinal axis and formed in cross section to conform to the interior of the 70 casing. In the form of my invention illustrated in the drawing, the magnets have taken the shape of an arc of a circle concentric with the casing. The magnets are fastened rigidly to the casing at points diametrically opposite each other. The magnets 12 and 13 are shorter than the others and are placed upon them nearer the center of the cylinder. Pole pieces are shown at 14. These pole pieces are so shaped that 75 they fill up the space at the end of the shorter magnet and are flush at their ends with the longer magnet.

In the drawing I have shown the parts connected together by screws, though I may 80 use any fastening means which will insure a rigid and permanent connection. The flux cutting member is shown consisting of two armatures rigidly connected together. These armatures 15 and 16 are constructed of 85 punchings which are fastened together making the well known H-shaped armature. As shown, they are connected together by the piece 17 and journaled in the hollow trunnions by short axles 18 and 19. The axle 19 90 is hollow. Through this hollow member an insulated contact leads to the electrical terminal 20 through which the current is taken. The armature conductor 21 is grounded at 95 22 forming the other terminal thereof. Upon the axle 19 I mount a cam 222 which rotates 100 with the armature and which is adapt'd to operate an electric switch 23—24, the object being to keep the armature short circuited until a certain point is reached when 105 the cam will operate to suddenly open this circuit causing a spark to go through the primary of the induction coil 25 and thence through its secondary to the engine. The member 17 is bored out along its principal 110 axis as shown at 30, and the conductor 21 passed therethrough. This prevents the use of rotating contact arrangements. The conductor is also protected from chafing to 115 which it would be subject if it were connected with the exterior of the connecting parts. By keeping it at the center I also avoid unbalancing the armature.

While I have shown the invention in this 120 particular form, it will be obvious to those skilled in the art that numerous and extensive departures from the form and the details of the apparatus here shown may be made without departing from the spirit thereof, the same being herein shown solely 125 for the purpose of clearly illustrating one specific embodiment.

I claim:

1. In a magneto electric machine, the combination of a closed casing mounted to rock, 130

a pair of straight bars mounted in said casing, one of said bars being longer than the other, said bars constituting field magnets for said machine, pole pieces at the end of 5 said bars and an armature in said casing adapted to be rotated to cut the flux of the field.

2. In a magneto electric machine, the combination of a closed casing, trunnions for 10 said casing, said casing being mounted to rock in said trunnions, a pair of straight bars mounted on the interior of said casing and adapted to be rocked therewith, one of said bars being longer than the other, the 15 longer bar being nearer the casing and having its ends projecting beyond the ends of the short bar, said bars being the field magnets of said machine, pole pieces between the ends of said bars and an armature in 20 said casing adapted to be rotated to cut the flux of said field.

3. In a magneto electric machine, the combination of a closed casing, trunnions for 25 said casing said casing being mounted to rock in said trunnions, a bar magnet mounted inside said casing to rock therewith, a second bar magnet mounted upon the inside

of said first bar magnet, said first named magnet being longer than said second named magnet and having its ends projecting beyond the ends of the first named magnet, pole pieces between the ends of said magnets and an armature in said casing adapted to be rotated to cut the flux of said magnets. 30

4. In a magneto electric machine, the combination of a closed casing, trunnions for 35 said casing, said casing being mounted to rock in said trunnions, a bar magnet mounted inside said casing to rock therewith, a second bar magnet mounted upon the inside 40 of said first bar magnet, said first named magnet being longer than said second named magnet and having its ends projecting beyond the ends of the second named magnet, pole pieces between the ends of said magnets 45 and a pair of armatures mounted in said casing to cut the flux of said magnet, said armatures being rigidly fastened together.

In testimony whereof I affix my signature in presence of two witnesses.

WILLIAM W. DEAN.
